ALFRED H. CLARK, OF BRIDGEPORT, CONNECTICUT.

AUTOMATIC ALARM-WHISTLE FOR MOTOR-CARS.

1,188,733.

Specification of Letters Patent. Patented June 27, 1916.

Application filed January 22, 1915. Serial No. 3,740.

To all whom it may concern:

Be it known that I, ALFRED H. CLARK, a citizen of the United States, residing at Bridgeport, county of Fairfield, State of Connecticut, have invented an Improvement in Automatic Alarm-Whistles for Motor-Cars, of which the following is a specification.

This invention has for its object to provide an exhaust operated whistle for motor-cars that may be easily operated to produce an alarm at crossings, corners or wherever required, by a simple movement of a key by foot or hand, and which by removal of the key will become a burglar alarm and will leave the mechanism in such condition that starting of the engine will automatically blow the whistle, the alarm being continuous so long as the engine is running, and it being impossible to stop the whistling except by insertion of the proper key.

With these and other objects in view I have devised the novel alarm whistle which I will now describe, referring to the accompanying drawing forming a part of this specification and using reference characters to indicate the several parts.

Figure 1 is a section of the floor of a motor-car showing the application thereto of the controlling mechanism of my novel alarm whistle; Fig. 2 an inverted plan view partly in section of the whistle and the valve mechanism, and Fig. 3 an elevation partly broken away corresponding with Fig. 2.

10 denotes the whistle which may be of any ordinary or preferred construction and has threaded engagement with a hub upon a valve body 11. The valve body is shown as provided with a clamp 12 by which it is removably secured to the exhaust pipe 13 of an engine.

21 denotes a chamber at one end of the body, 14 a valve seat within the chamber, 15 the disk and 16 the stem which passes through a housing 17. The stem is provided with a collar 18 within the housing, and a spring 19 bearing against the outer end of the housing and the collar acts to normally hold the disk in the closing position, so that the exhaust cannot escape through the valve but must pass through the whistle and cause an alarm. The housing valve, and stem are carried by a bridge piece 20 which crosses but does not close the open outer end of the chamber. The bridge piece is shown as secured to the valve body by a

pin 22 which engages the parts with a drive fit and a stud 23 which has a reduced end passing through the bridge piece and having threaded engagement with the body. A 60 valve lever 24 has its fulcrum in the outer end of the stud and one arm thereof is pivoted to the outer end of the valve stem.

Turning now to Fig. 1, 25 denotes the floor of a motor-car in which is secured a 65 casing 26 having a face plate 27 secured to the floor. 28 denotes a bell crank lever fulcrumed in the casing and having a relatively long arm extending outside of the casing which is connected by means of a chain or 70 cord 29 with the free arm of lever 24. The other arm of the bell crank lever is suitably shaped for engagement by a key 30 in the casing. This key is adapted to be inserted through a slot 31 in the face plate and is 75 provided with a shoulder 32 which is adapted to engage the under side of the face plate at one end of the slot, as at 33. A spring 34 within the casing bears against the edge of the key opposite to the edge having the 80 shoulder and forces the key forward retaining the shoulder in engagement with the face plate, as shown in full lines in Fig. 1. The upper end of the key is shown as provided with a handle or foot piece formed by twisting the metal. It will of course be obvious that the location of this controlling mechanism or whether it is operated by the hand or the foot is immaterial so far as the principle of the invention is concerned. 90

The operation is as follows: Spring 19 is strong enough to close the valve the instant it is permitted to do so by the controlling mechanism, the closing position being indicated by dotted lines in Fig. 2. When the 95 valve is opened, see full line position in Fig. 2, the exhaust will naturally follow the path of least resistance and pass out through chamber 21. When the valve is closed, however, the exhaust must pass out through the 100 whistle and sound an alarm. The normal running position of the controlling mechanism is as shown in Fig. 1, the shoulder upon the key being retained in engagement with the face plate by spring 34. To sound 105 an alarm the operator kicks or pushes the key backward against the power of spring 34. The instant the key is disengaged spring 19 will close the valve and will move the bell crank lever and key to the dotted 110 line position in Fig. 1. The alarm will continue so long as the parts remain in this po-

sition. To stop the alarm it is simply required to push the key downward which will swing the bell crank lever to the full line position and will lift the valve disk away from the seat against the power of spring 19, as in Fig. 2, which stops the alarm. The instant the shoulder on the key passes below the face plate, spring 34 will move the key to the engaging position, as in full lines in Fig. 1, and lock the valve in the open position.

Suppose now that the operator desires to leave the car and wishes the alarm sounded should anyone attempt to start it. He simply disengages the key as before and removes it, which permits spring 19 to close the valve as before. Should anyone start the car now, the exhaust from the engine will sound the whistle and the alarm will continue until the engine is stopped or until the alarm is stopped by insertion and proper manipulation of the key, to cause the bell crank lever to open the valve.

Having thus described my invention, I claim:

1. An alarm of the character described comprising an exhaust operated whistle, a valve adapted to permit escape of the exhaust without sounding the whistle, a spring for closing the valve, controlling connections and a removable key which normally retains the valve open against the power of the spring.
2. An alarm of the character described comprising an exhaust operated whistle, a valve adapted to permit escape of the exhaust without sounding the whistle, a spring for closing the valve, a valve lever, and controlling mechanism comprising a bell crank lever, a connection between said bell crank lever and the valve lever and a removable key adapted to engage the bell crank lever to lock the valve open against the power of the spring.
3. In combination in an alarm, an exhaust operated whistle, a valve adapted to permit escape of the exhaust without sounding the whistle, a spring for closing the valve, a valve lever, and means for operating the valve lever comprising a bell crank lever, a casing in which said bell crank lever is pivoted and which is provided with a face plate having a slot, a removable key adapted to be passed into the slot and to engage the bell crank lever and means for retaining the key in the operative position.
4. In combination in an alarm, an exhaust operated whistle, a valve adapted to permit escape of the exhaust without sounding the

whistle, a spring for closing the valve, a valve lever, and means for operating the valve lever comprising a bell crank lever, a casing in which said bell crank lever is pivoted and which is provided with a face plate having a slot, a removable key provided with a shoulder and adapted to be passed into the slot and to engage the bell crank lever, and a spring acting to retain the shoulder in engagement with the face plate at one end of the slot to lock the valve in the open position.

5. In combination in an alarm, a valve body having means for attachment to a pipe and at the other end an open chamber, a whistle attached to the body, a valve seat in the chamber, a spring pressed disk adapted to engage the seat, means for raising the disk against the power of the spring and a removable key adapted to lock the disk in the raised position.

6. In combination in an alarm, a valve body having means for attachment to a pipe and at the other end an open chamber, a whistle attached to the body, a valve seat in the chamber, a spring pressed disk adapted to engage the seat and provided with a stem, a valve lever pivoted to the stem, a bell crank lever, a connection between said levers and a removable key adapted to engage the bell crank lever to lock the disk in the raised position.

7. In combination in an alarm, a valve body having means for attachment to a pipe and at the other end an open chamber, a whistle attached to the body, a valve seat in the chamber, a spring pressed disk adapted to engage the seat and having a stem, a valve lever pivoted to said stem, a bell crank lever and connections to the valve lever, and a removable key adapted to lock the disk in the raised position.

8. In combination in an alarm, a valve body having means for attachment to a pipe and at the other end an open chamber, a whistle attached to the body, a valve seat in the chamber, a spring pressed disk adapted to engage the seat, a bell crank lever and connections to the valve lever, a removable key adapted to engage the bell crank lever and a spring acting to retain the key in a locking position with the valve raised.

In testimony whereof I affix my signature in presence of two witnesses.

ALFRED H. CLARK.
